Attorney

UNITED STATES PATENT OFFICE.

HUGO RECKMANN, OF ALTONA-ELBE, GERMANY.

SLIDING DEVICE FOR SAILS.

Application filed September 14, 1925, Serial No. 56,285, and in Germany May 28, 1925.

This invention relates to a sliding device for sails which, in comparison with the commonly used devices, facilitates considerably the hoisting and taking in of sails owing to its special construction. According to the invention a guide bar is fixed along the mast and sliding bodies are movably mounted in said bar the sail being attached to pins rotatably mounted in said sliding bodies.

An embodiment of the invention is shown, by way of example, on the accompanying drawing in which

Fig. 1 shows the device in side elevation.

Fig. 2 is a front elevation showing part of the device on larger scale than in Fig. 1.

Fig. 3 is a cross section of Fig. 2.

Fig. 4 is a side elevation of Fig. 2.

Fig. 5 shows in cross section a modified arrangement according to which the guide bar is sunk into the mast, this arrangement being preferably designed for gaff-sails.

Fig. 6 shows in elevation the device as shown in Fig. 5 used for attaching a gaff-sail.

According to the invention a guide bar *b* is fixed along the mast *a*. In this guide bar *b* sliding bodies *c* are movably mounted which have each a rotatable pin *d*. Each pin *d* has eyes *f* at the upper and lower ends to which the sail is attached. Collars *g* at the upper and lower ends of the pins *d* serve to guide the sail when it changes its position so that the sail can freely move and does not come in contact with the slide *c*.

In order to ensure an easy movability of the sliding bodies *c* in the guide bar *b*, i. e. to ensure a movement free from friction, the sliding bodies *c* have each preferably lateral horizontal studs *e* near the upper and lower ends which are of circular cross section so that the contact surfaces moving with friction are reduced as much as possible.

As the pins *d* to which the sail is attached can freely rotate the sail can freely swing in lateral directions.

The improved sliding device can be used for high sails without gaff and for gaff-sails. When this device is used the space between the sail and the mast is narrower than with any of the commonly used arrangements. Owing to the narrowest possible gap between sail and mast the best possible utilization of the wind and the utmost effect of the said are ensured.

The guide bar *b* is sunk into the mast as shown in Figs. 5 and 6 when the device is to be used for gaff-sails in order that the gaff-shoe can freely slide up and down the mast.

I claim:—

1. A sliding device for sails comprising in combination with the mast, a guide bar fixed on the mast, sliding bodies movably mounted in said guide bar, a pair of studs on each of said sliding bodies arranged the one above the other and slidably engaging with said guide bar, a rotatable pin in each of said sliding bodies and two eyes fixed on said pin to which eyes the sail is attached.

2. A sliding device for sails comprising in combination with the mast, a guide bar fixed on the mast, sliding bodies movably mounted in said guide bar, a pair of studs on each of said sliding bodies arranged the one above the other and slidably engaging with said guide bar, a rotatable pin in each of said sliding bodies, two eyes fixed on said pin to which eyes the sail is attached, and a collar on each rotatable pin for preventing the sail when sliding to come in contact with said sliding bodies.

In testimony whereof I affix my signature.

HUGO RECKMANN.
